Patented Jan. 2, 1917.

FIG. 4.

FIG. 5.

INVENTOR:

Geo. B. Chadwick,

By E. D. Chadwick,
Attorney.

UNITED STATES PATENT OFFICE.

GEORGE B. CHADWICK, OF PORTSMOUTH, NEW HAMPSHIRE.

REAMER HAVING DETACHABLE BLADES.

1,210,903.

Specification of Letters Patent. Patented Jan. 2, 1917.

Application filed February 24, 1916. Serial No. 80,292.

To all whom it may concern:

Be it known that I, GEORGE B. CHADWICK, a citizen of the United States, residing at Portsmouth, in the county of Rockingham 5 and State of New Hampshire, have invented certain new and useful Improvements in Reamers Having Detachable Blades, of which the following is a specification.

This invention, which is applicable to various types of reamers, taps and similar tools having detachable blades, is particularly intended to provide a tool of this character which will operate without danger of breakage or distortion of the blades by the strains imposed upon them when in use, even though the blades are relatively long, and also to provide an improved arrangement for adjusting the blades inward and outward to vary the effective diameter of the tool. The construction by which the foregoing objects are accomplished is particularly applicable to expandible reamers of that type in which the blades extend slightly beyond the forward end of the body of the reamer and hence are effective for reaming the entire length of a cylindrical bore having a closed bottom, and such a reamer is illustrated in the accompanying drawing, in which:

Figure 1 is a side elevation of the reamer, as preferably constructed; Fig. 2 shows the reamer partly in side elevation and partly in central longitudinal section; Fig. 3 is a transverse section on the line 3—3 in Fig. 2; Fig. 4 is a side elevation of the front end of the driving mandrel of the reamer; Fig. 5 is a rear elevation of the same; Fig. 6 shows in edge view a number of graded adjusting shims hereinafter described; Fig. 7 is a similar view showing tapering shims; and Fig. 8 is a side elevation of one of the detachable blades.

The reamer illustrated in the drawing comprises a driving mandrel 2, having at its front end a cylindrical enlargement 3 which constitutes a unitary part of the mandrel and is provided with a number of notches 4, each of which extends radially inward from the periphery of the enlargement and also longitudinally through the latter. These notches 4 correspond in number with the detachable blades 5 employed

in the reamer, eight being shown, although the precise number is immaterial. The enlargement 3 is also provided on its rear face 55 with a like number of rearwardly-extending projections 6, each of which is located at the bottom of one of the notches 4 and has its rear face 7 slanted inward and forward, its outer face being preferably flush with the 60 bottom of the corresponding notch. On the mandrel 2 is mounted a cylindrical shell 8 provided externally with longitudinally-extending radial grooves 9 which correspond in number, width and position with the 65 notches 4 but are enough deeper than the latter to receive the projections 6, so that the front end of the shell is adapted to abut against the rear face of the enlargement 3 with said projections lying in the front ends 70 of the respective grooves 9. The shell 8 is clamped in this position by means of a nut 10 mounted on a threaded portion 11 of the mandrel 2 and bearing against the rear end of said shell.

In each of the grooves 9 and the corresponding notch 4 is located one of the blades 5, the inner portion of which is cut away at its front end to provide an angular recess 12 adapted to receive the corresponding projection 6, as shown in Fig. 2, the inner edge 80 of the blade being supported either by the shell 8 when the reamer is fully contracted or by one of the adjusting devices herein-after described when the reamer is expanded. The outer edge 13 and the front edge 14 of each blade 5 constitute cutting edges, which ordinarily extend at right angles to each other, and when the blade is placed in position as above described these cutting 85 edges project respectively beyond the adjacent faces of the shell 8 and enlargement 90 3. All of the blades employed, which are exactly alike, are simultaneously clamped in place by means of a concave nut 15 mounted 95 on an externally threaded portion of the shell 8 and bearing against the slanting rear ends 16 of the several blades in the usual way.

It is well understood that in a reamer having detachable blades the several blades employed cannot be spaced equally around the body of the reamer without causing it to chatter when in use, and hence it is custom-

ary to locate the blades at slightly unequal distances apart in a circumferential direction. It is therefore necessary, in order to cause the corresponding notches 4 and 5 grooves 9 to register, to apply the shell 8 to the mandrel 2 in a specific position, and to facilitate the assembling of these parts I provide a pin 17 extending transversely through the mandrel immediately behind the 10 enlargement 3 and having its projecting ends so located that when they are received within notches 18 formed in the front end of the shell 8 the grooves 9 in the latter are properly positioned with respect to the 15 notches 4, the assembled parts being held in this position by the clamping nut 15 already described.

It will be seen that when the reamer above described is in use the driving power applied to the mandrel is carried forward and transmitted to the blades at their front ends, where the heaviest duty is imposed upon them, and that the rear portions of the blades are practically free from twisting 20 strains, since they have but little cutting work to do and act mainly as guides in that portion of the bore which has already been reamed by the front ends of the blades. This 25 is an important advantage over prior reamers, in which the driving torque is applied mainly at the rear ends of the blades or indiscriminately throughout their length and has been found to result in many cases in either breaking the blades or distorting them 30 sufficiently to prevent the reaming operation from forming a true surface. Such distortion cannot occur in the reamer above described, since the only positive force by which the shell 8 is rotated is transmitted 35 thereto through the blades themselves, in conjunction with the projections 6 and the pin 17.

For the purpose of adjusting the blades radially and thereby varying the effective 40 diameter of the reamer I provide one or more sets of shims 19 of graded thicknesses, three such shims being shown in Fig. 6. All 45 of the shims in any one set have the same thickness and are adapted to be severally located in the grooves 9 beneath the corresponding blades 5, so that the radial position of the latter will depend on the thickness of the shims in the set employed in any given instance, while when no shims are in 50 use the blades rest directly on the shell 8 and the reamer will be adjusted to its minimum diameter. When a set of shims are located in the grooves 9 the blades are displaced rearwardly to a slight extent, owing 55 to the engagement of the blades with the slanting faces 7 of the projections 6, but in all positions of adjustment these projections enter the angular recesses 12 to a sufficient extent to hold the front ends of the blades 60 in the notches 4.

The above-described arrangement for adjusting the blades radially has the advantage that by employing tapering shims, shown at 20 in Fig. 7, the other parts of the reamer may be utilized without alteration 70 to provide a taper reamer, the angle of which will depend upon the taper of the shims employed. In such case each blade will be tilted slightly with respect to the bottom of the corresponding notch 4, on 75 which it will rest at the front end of the notch only, but the projections 6 will still be effective to hold the front ends of the blades in position as previously explained.

While I prefer to employ shims as above 80 described for adjusting the blades, because they afford rigid support for the inner edges of the blades and prevent any possibility of accidental variation of the adjustment when the tool is in use, it will be understood that 85 various other means for adjusting the blades may be employed, if preferred, without losing the advantages resulting from the above-described arrangement for driving the blades, and it will also be understood that my blade- 90 driving arrangement can be utilized to advantage in various forms of reamers and other tools having detachable blades, whether the blades have projecting front ends or not, and whether their inner and outer edges are 95 parallel or otherwise. The details of construction of the mandrel and sleeve and of the means employed for securing the blades in place can also be modified in various ways without departing from the scope of the 100 appended claims.

I claim:

1. A tool of the character described, comprising a driving mandrel having a unitary enlargement provided with blade-receiving 105 notches, a shell mounted on the mandrel behind said enlargement and provided with blade-receiving grooves in alignment with the corresponding notches, a set of blades located in said grooves and notches, and 110 means for securing the blades in place.

2. A tool of the character described, comprising a driving mandrel having a unitary enlargement provided with blade-receiving 115 notches, a shell mounted on the mandrel behind said enlargement and provided with blade-receiving grooves in alignment with the corresponding notches, a set of blades located in said grooves and notches, means for adjusting the blades radially, and means 120 for securing the blades in place.

3. A tool of the character described, comprising a driving mandrel having at its front end a unitary enlargement provided with blade-receiving notches, a shell mounted on the mandrel behind said enlargement and provided with blade-receiving grooves in alignment with the corresponding notches, a set of blades located in said grooves and notches and having at their front ends 130

transverse cutting edges projecting beyond said enlargement, and means for securing the blades in place.

4. A tool of the character described, comprising a driving mandrel having a unitary enlargement provided with blade-receiving notches and with rearwardly-extending projections each located behind one of said notches, a shell mounted on the mandrel behind said enlargement and provided with blade-receiving grooves in alinement with the corresponding notches, a set of blades located in said grooves and notches and having recesses to receive said projections, whereby the front ends of the blades are held against outward movement, and means for clamping the blades in place.

5. A tool of the character described, comprising a driving mandrel having at its front end a unitary enlargement provided with blade-receiving notches and with rearwardly-extending projections each located behind one of the notches, a shell mounted on the mandrel behind said enlargement and provided with blade-receiving grooves in alinement with the corresponding notches, a set of blades located in said grooves and notches and having recesses to receive said projections, said blades being provided with longitudinal and transverse cutting edges located respectively outside of the shell and in front of said enlargement, and means for clamping the blades in place.

6. A tool of the character described, comprising a driving mandrel having a unitary enlargement provided with blade-receiving notches and with rearwardly-extending projections each located behind one of the notches and having a slanting rear face, a shell mounted on the mandrel behind said enlargement and provided with blade-receiving grooves in alinement with the corresponding notches, a set of blades located in said grooves and notches and each having a slanting rear end and an angular recess adapted to receive the corresponding projection, means for adjusting the blades radially, and a clamping nut mounted on the shell and arranged to engage the rear ends of the blades.

7. A tool of the character described, comprising a driving mandrel having at its front end a unitary enlargement provided with blade-receiving notches and with rearwardly-extending projections each located behind one of the notches and having a slanting rear face, a shell mounted on the mandrel behind said enlargement and provided with blade-receiving grooves in alinement with the corresponding notches, a set of blades located in said grooves and notches and each having a slanting rear end and an angular recess adapted to receive the corresponding projection, said blades being provided with longitudinal and transverse cut-

ting edges located respectively outside of the shell and in front of said enlargement, means for adjusting the blades radially, and a clamping nut mounted on the shell and arranged to engage the rear ends of the blades.

8. A tool of the character described, comprising a body portion having blade-receiving grooves and a set of detachable blades adapted to be located therein, means for adjusting the blades radially comprising sets of shims adapted to be located beneath the respective blades, the shims in each set being of the same thickness and those in the different sets being of graded thicknesses, and means for securing the blades in place.

9. A tool of the character described, comprising a driving mandrel having a unitary enlargement provided with blade-receiving notches, a shell mounted on the mandrel behind said enlargement and provided with blade-receiving grooves in alinement with the corresponding notches, a set of blades located in said grooves and notches, a set of shims of equal thickness located beneath the respective blades, and means for securing the blades in place.

10. A tool of the character described, comprising a driving mandrel having a unitary enlargement provided with blade-receiving notches and with rearwardly-extending projections each located behind one of the notches, a set of blades having their front end portions located in the respective notches and provided with recesses to receive the corresponding projections, a set of shims of equal thickness located beneath the respective blades, and a clamping nut arranged to engage the rear ends of the blades.

11. A tool of the character described, comprising a driving mandrel having a unitary enlargement provided with blade-receiving notches and with rearwardly-extending projections each located behind one of the notches and having a slanting rear face, a shell mounted on the mandrel behind said enlargement and provided with blade-receiving grooves in alinement with the corresponding notches, a set of blades located in said grooves and notches and each having a slanting rear end and an angular recess adapted to receive the corresponding projection, a set of shims of equal thickness located beneath the respective blades, and a clamping nut mounted on the shell and arranged to engage the rear ends of the blades.

12. A tool of the character described, comprising a driving mandrel having at its front end a unitary enlargement provided with blade-receiving notches and with rearwardly-extending projections each located behind one of the notches and having a slanting rear face, a shell mounted on the mandrel behind said enlargement and provided with blade-receiving grooves in aline-

ment with the corresponding notches, a set of blades located in said grooves and notches and each having a slanting rear end and an angular recess adapted to receive the corresponding projection, said blades being provided with longitudinal and transverse cutting edges located respectively outside of the shell and in front of said enlargement, a set

of shims of equal thickness located beneath the respective blades, and a clamping nut 10 mounted on the shell and arranged to engage the rear ends of the blades.

Signed at Boston, Mass., this 23rd day of February, 1916.

GEORGE B. CHADWICK.
